DESIGN FOR AN ELECTRIC FAN UNIT

Rolland C. Sabins, Wisconsin Rapids, Wis.

Application March 30, 1940, Serial No. 91,361

Term of patent 7 years

To all whom it may concern:

Be it known that I, Rolland C. Sabins, a citizen of the United States, residing at Wisconsin Rapids, in the county of Wood and State of Wisconsin, have invented a new, original, and ornamental Design for an Electric Fan Unit, of which the following is a specification, reference being had to the accompanying drawing, forming a part thereof.

Figure 1 is a front elevational view of an electric fan unit showing my new design;

Figure 2 is a view of the fan unit as seen from the rear;

Figure 3 is a view of the fan unit as seen from the right;

Figure 4 is a view of the fan unit as seen from above; and

Figure 5 is a view of the fan unit as seen from below.

I claim:

The ornamental design for an electric fan unit, as shown.

ROLLAND C. SABINS.
